UNITED STATES PATENT OFFICE.

WILLIAM McCALLUM, OF SOUTH ORANGE, NEW JERSEY, ASSIGNOR TO THE
BIGELOW CARPET COMPANY, OF CLINTON, MASSACHUSETTS.

DESIGN FOR A CARPET.

SPECIFICATION forming part of Design No. 14,394, dated November 6, 1883.

Application filed January 17, 1883. Term of patent 3½ years.

To all whom it may concern:

Be it known that I, WILLIAM McCALLUM, of South Orange, county of Essex, State of New Jersey, have invented a new and original Design for Carpets, of which the following is a specification.

This invention relates to a new and original design for carpets and similar fabrics; and it consists in the novel grouping and configuration of parts, hereinafter more fully described.

The accompanying photograph illustrates a face view of a carpet having my new design.

G B is a band, the two portions B and G being separated by a beaded border, and the lower portion, B, of the band having ornamentation resembling twining leaves. D is a stripe, along the top of which runs a border, a, ornamented with a double row of figures resembling crosses. The stripe D also contains a vine-like figure curving through it and

consisting of slender tendrils, on which appear the flowers r and b, also leaves e, and flowers t, s, and d. The whole effect of the stripe is that of a plain background, over which curves the vine bearing various flowers and leaves. 25

I claim—

1. The design for carpets, consisting of the stripe D, containing figures r b e t s d, substantially as shown.
2. The design for carpets, consisting of the band a and stripe D, containing figures r b e t s d, substantially as shown.
3. The design for carpets, consisting of the band B G, band a, and stripe D, containing figures r b e t s d, substantially as shown.

WILLIAM McCALLUM.
